UNITED STATES PATENT OFFICE.

JAMES H. KNAPP, OF LOS ANGELES, CALIFORNIA.

HEATING FURNACE.

Application filed November 27, 1923. Serial No. 677,215.

To all whom it may concern:

Be it known that I, JAMES H. KNAPP, a citizen of the United States, residing at Los Angeles, in the county of Los Angeles and 5 State of California, have invented a new and useful Improvement in Heating Furnaces, of which the following is a full, clear, and exact description.

The present invention relates to heating 10 furnaces employed for the heat treatment of metal or other material, and more particularly to heating furnaces of the car type.

In heating furnaces, particularly in heating furnaces of the car type, the difficulty 15 is generally encountered of a cold bottom, due to the fact that the top of the heating chamber of such a furnace is heated not only directly by the hot gases of combustion sweeping from the top of the bridge wall, 20 but also by radiation over the roof of the chamber, whereas the bottom of the chamber depends for its heat primarily upon the gases flowing therethrough which have already given up a large portion of their heat 25 in passing through the upper portion of the chamber. Furthermore, in the operation of a heating furnace of the car type the movable bottom when taken out of the furnace 30 cools off, so that when it is replaced in the furnace it is relatively cool as compared with the side walls and roof of the heating chamber, which adds to the difficulty of rapidly warming up the lower portion of the heating chamber.

By the present invention I propose to overcome the above difficulty in a heating furnace by the provision in the lower portion of the bridge wall thereof of relatively thin shields of heat-resisting and heat-conducting material the function of which is to quickly transmit heat from the combustion chamber to the bottom and lower portion of the heating chamber of the furnace.

In the accompanying drawings, there is 45 shown, for purposes of illustration only, one embodiment of the present invention, it being understood that the drawings do not define the limits of the invention, as changes may be made in the construction and operation therein disclosed without departing from the spirit of the invention or scope of my broader claims.

In the drawings—

Figure 1 is a vertical transverse sectional view of a heating furnace of the car type embodying my invention, the said furnace

having combustion chambers at one side thereof only;

Figure 2 is a vertical longitudinal sectional view on the line II—II of Figure 1; 40

Figure 3 is a fragmentary sectional view on the line III—III of Figure 1;

Figure 4 is a fragmentary sectional view on the line IV—IV of Figure 2;

Figure 5 is a vertical transverse sectional 45 view of a furnace of the car type, having combustion chambers on opposite sides of the heating chamber; and

Figure 6 is a sectional view through one 50 side of the furnace shown in Figure 5, the section being partly in the plane represented by the upper horizontal portion of the line 70 VI—VI of Figure 5 and partly in the plane represented by the lower horizontal portion 75 of said line.

Referring to the embodiment of the invention illustrated in Figures 1 to 4, inclusive, the reference numeral 2 indicates a furnace of the car type having a heating chamber 3 the charging opening 4 of which 80 is closed by a door 5 adapted to be operated by any suitable means. The heating chamber is provided with the usual movable bottom 6 provided with flanged wheels 7 by 85 which the said bottom is supported for movement upon tracks 8 whereby the bottom may be moved into and out of the furnace.

The furnace is provided at one side thereof 90 with combustion chambers 9 separated from the heating chamber by a bridge wall 10. The fuel, which may be oil or gas, is introduced into the combustion chambers through 95 burner openings 11 and the hot combustion gases pass from the combustion chambers over the top of the bridge wall into the top portion of the heating chamber. These gases flow downwardly through the heating chamber and pass out of the furnace 100 through outlet ports 12 located near the hearth level.

As already pointed out, in a furnace of this type as ordinarily constructed the top portion of the heating chamber warms up 105 much more rapidly than the bottom portion thereof, causing the difficulty commonly referred to as "cold bottom." In order to overcome this defect, I provide openings 13 in the lower portion of the bridge wall and close such openings by relatively thin shields 14 of heat-resisting and heat-conducting material. The shields are preferably formed,

- as shown, of silicon carbide, as this material is highly refractory and is, therefore, capable of withstanding high temperatures even when employed in relatively thin slabs.
- 5 However, my invention is not limited to the use of this particular material, as a heat-resisting alloy or other suitable material may be employed if desired. These shields are adapted to radiate heat directly onto the 10 bottom of the heating chamber, and being very thin in proportion to the thickness of the bridge wall and of a high heat-conducting material, they become red hot and a radiating medium very soon after the furnace 15 has been lighted. By reason of these shields in the lower portion of the bridge wall, it is possible to warm up the bottom portion of the heating chamber almost as rapidly as the top portion thereof.
- 20 In Figures 5 and 6 I have illustrated my invention as embodied in a heating furnace of the car type having combustion chambers on both sides of the heating chamber. In this construction of furnace each bridge wall 25 15 is provided in the lower portion thereof with openings 16 in which are placed shields 17 of heat-resisting and heat-conducting material.
- While I have illustrated my invention as 30 embodied in heating furnaces of the car type, it will be apparent that the invention also has utility in connection with heating furnaces of the solid hearth type, that is, furnaces in which the hearth is stationary. The 35 invention is, therefore, not limited to the particular type of furnace nor to the details of construction shown, as it may be otherwise embodied within the scope of the appended claims.
- 40 I claim:
1. A heating furnace comprising a heating chamber, a combustion chamber, and a bridge wall separating said chambers, said bridge wall having a relatively thin lower 45 portion formed of heat-resisting and heat-conducting material, substantially as described.
2. A heating furnace comprising a heating chamber, a combustion chamber, a bridge 50 wall separating said chambers and having an opening in the lower portion thereof, and a shield of heat-resisting and heat-conducting material closing said opening, substantially as described.
- 55 3. A heating furnace comprising a heating chamber, a combustion chamber, a bridge wall separating said chambers and having an opening in the lower portion thereof, and a shield of heat-resisting and heat-conducting material of less thickness than said bridge wall closing said opening, substantially as described.
- bridge wall separating said chambers and having an opening in the lower portion thereof, and a shield of heat-resisting and heat-conducting material of less thickness than said bridge wall closing said opening, substantially as described.
4. A heating furnace comprising a heating chamber, a combustion chamber, and a wall interposed between said heating chamber and said combustion chamber, said wall having a relatively thin lower portion formed of heat-resisting and heat-conducting material, substantially as described.
5. A heating furnace comprising a bridge wall provided with openings in the lower portion thereof, and relatively thin shields of heat-resisting and heat-conducting material closing said openings, substantially as described.
6. A heating furnace comprising a heating chamber, a combustion chamber, a bridge wall separating said chambers and having an opening in the lower portion thereof, and a relatively thin shield of silicon carbide closing said opening, substantially as described.
7. A heating furnace comprising a heating chamber, combustion chambers at opposite sides of said heating chamber, bridge walls separating said heating chamber from said combustion chambers and each having an opening in the lower portion thereof, and relatively thin shields of heat-resisting and heat-conducting material closing said openings, substantially as described.
8. A heating furnace comprising a heating chamber having a movable bottom, a combustion chamber, a bridge wall separating said chambers and having an opening in the lower portion thereof, and a relatively thin shield of heat-resisting and heat-conducting material closing said opening, substantially as described.
9. A heating furnace comprising a heating chamber having a movable bottom, combustion chambers at opposite sides of said heating chamber, bridge walls separating said heating chamber from said combustion chambers and each having an opening in the lower portion thereof, and relatively thin shields of heat-resisting and heat-conducting material closing said openings, substantially as described.

In testimony whereof I have hereunto set my hand.

JAMES H. KNAPP.
